UNITED STATES PATENT OFFICE.

WILLIAM F. OLIN, OF CHICAGO, ILLINOIS.

GRAIN-HARVESTER.

SPECIFICATION forming part of Letters Patent No. 415,279, dated November 19, 1889.

Application filed February 13, 1888. Serial No. 263,863. (No model.)

To all whom it may concern:

Be it known that I, WILLIAM F. OLIN, a citizen of the United States, residing in the city of Chicago, county of Cook, and State of Illinois, have invented certain new and useful Improvements in Grain-Harvesters, which are fully set forth in the following specification, reference being had to the accompanying drawings, forming part thereof.

Figure 1 is a partly sectional plan of a harvester embodying my invention, many parts not related thereto being omitted. Fig. 2 is a plan of a modification of the platform-conveyer frame with its connections and its operating mechanism. Fig. 3 is a vertical section through the platform on the line $x-x$ of Fig. 1, but showing the mechanism in a different position from that shown in Fig. 1. Fig. 4 is a section on the line $y-y$ of Fig. 1. Fig. 5 is a perspective of a universal joint pertaining to the platform-conveyer and cutting mechanisms. Fig. 6 is a plan of a portion of the harvester-frame stripped of mechanism, designed to show the mode in which the several sills and bars of the frame are joined and arranged to brace and stiffen each other. Fig. 7 is a vertical section at the line $x'-x'$ on Fig. 1. Fig. 8 is an enlarged detail plan of a portion of the finger-bar and its connected fingers and of the sickle, designed to show the relative arrangement of the fingers and the direction of their gathering-edges. Fig. 9 is a section through the line $y'-y'$ on Fig. 1. Fig. 10 is a front elevation of the binder-frame and driving-train. Fig. 11 is a section through the line 11 11 on Fig. 10. Fig. 12 is a section through the line 12 12 on Fig. 1. Fig. 13 is a section through the line 13 13 on Fig. 1. Fig. 14 is a front elevation of the binder-shifting lever and connected mechanism, showing the sill upon which it is supported in section.

The harvester-frame is constructed as follows: There are two sills A A', extending from front to rear, the former on the outer side and the latter on the inner side of the drive-wheel. They are connected at their forward ends by a bar or sill A², which crosses and is securely fastened to them both at their forward ends and extends thence grainward, and is united to the finger-bar B by means

which will be hereinafter described. Said sills are further united by the bar or sill A³, which crosses and is firmly secured to them both at their rear ends, and thence is bent 55 obliquely forward and grainward, extending, without further change of direction, nearly to the vertical plane of the drive-wheel axis, being then again bent more grainward and extending a short distance. The last portion 60 A³ extends alongside of and is securely bolted to a flat metal bar A⁴, placed vertically edge-wise and having one end A⁴ bent at an oblique angle to its general extent, so as to lie alongside the sill A', to which it is securely fastened. 65 Said bar A⁴ extends in the oblique direction first indicated, forward and grainward, and is joined to the stubbleward end of the finger-bar B a short distance stubbleward from the connection of said finger-bar to the bar A², 70 above mentioned.

By means of a bracket C', which will be hereinafter more particularly described, the rear sill or bar A⁵ is secured to the sill A', and from said securement extends first at an angle of about forty-five degrees to the sill A', 75 rearward and grainward until it reaches a point somewhat farther grainward than the junction of the sill A² to the finger-bar, and is there bent directly grainward, and at its 80 grain end is rigidly secured to the grainward or divider sill or bar A⁶. Said divider-sill A⁶ extends from its securement to the rear sill A⁵ forward, with a slight grainward obliquity, and crosses and is secured to the finger-bar 85 at the grain end thereof, and, extending forward of it, is provided with the usual appliances of a divider. Where the rear sill A⁵ crosses the obliquely-extending portion of the sill A³ it is preferably rigidly secured thereto, and it may be secured, also, at its intersection with the bar A⁴. 90

Upon inspection of this frame it will be seen that the triangles formed, first, by the sill A', bar A², and bar A⁴, taken with the 95 short portion of the finger-bar which completes the junction between the bars A² and A⁴, second, by the sill A', bar A⁴, and bar A³, and, third, by the sill A', bar A³, and sill A⁵, make a structure which is very rigidly braced 100 against fore-and-aft strain which might tend to result from rearward pressure or resistance

to forward motion encountered by the finger-bar. To further stiffen this structure, the bar A⁴ is connected to the sill A⁵ by the bar A⁷, which is secured to bar A⁴ near the junction of the latter with the finger-bar B, and to the sill A⁵ at a point grainward from the bend a⁵, where it turns directly grainward, thus making an irregular triangle, of which bar A⁷ forms one side, the bar A³ forms another, and the bar A⁴ and the portion of the bar A³ from its intersection with sill A⁵ to its junction with bar A⁴ forms the third side. The triangle formed by bars A² and A⁴ and sill A⁵ is also stiffened by the brace A⁸, which is secured to bars A⁴ and A², and affords securement for certain brackets, which afford the bearings for the gearing, as will be hereinafter specifically explained. The bar A⁷ is further stiffened by the bar A⁹, which extends from the first-named bar to the sill A⁵ at a distance from the forward end of bar A⁷ about one-third of its length, and from said bar A⁹ is extended the bar A¹⁰, which crosses and is rigidly secured to the bar A⁴, thereby stiffening it.

For convenience of reference hereinafter the sills A A' and the front sill A² and rear sill A³, said four sills inclosing the wheel, may be referred to as the "wheel-frame," and the sill A⁵ and the oblique portion of the sill A³, the bar A⁴, and the finger-bar, and the various braces, bars, and sills which stiffen and connect these several parts may be referred to as the "platform-frame."

D is the drive-wheel. D' is the master-wheel, rigid therewith. The drive-wheel axle is journaled in a journal-box c' on the sill A, and in a suitable bearing provided in the bracket C', which is secured to the sill A' and affords securement, as above stated, for the rear sill A⁵. To the sill A' there is secured, also, the bracket C², which has a bearing for the shaft of the main driving-pinion D², which meshes with and is driven by the master-wheel D', said shaft d² having secured to its grainward end the beveled gear-wheel D³. Said gear-wheel meshes with and drives the beveled pinion D⁴, whose shaft d⁴ has a bearing in the bracket C².

C³ is a bracket, which is secured to the bar A¹⁰ and to the brace A⁸. It has a bearing C³⁰ for the shaft d⁴, near its forward and grainward end, and said shaft carries at that end the beveled gear-wheel D⁵, which meshes with and drives the beveled gear D⁶, which also has a bearing C³¹ in the bracket C³, and meshes with and drives the beveled gear D⁷, fixed on the stubbleward end of the shaft d¹⁰, which has a bearing C³² in said bracket C³ in line with that of the shaft d⁴. The purpose of the beveled gear-wheel D⁶ is to communicate power to the binder, and its further bearings will be hereinafter explained.

The bars A², A³, A⁵, and A⁶ and the finger-bar B are all made of angle-iron, having one flange vertical and the other horizontal, thereby affording convenient surfaces for the

attachment of the bars to each other and to other parts of the frame-work and brackets and giving rigidity in both vertical and horizontal directions.

The bracket C has a flange which is secured to the horizontal flange of the bar A², and is formed with an angle portion which fits into the angle of the finger-bar B, to whose vertical flange it is bolted. This bracket has the bearing c for the grainward end of the shaft d¹⁰, said bearing being above the securement of the bracket to the bar A². To the end of the shaft d¹⁰, grainward from the bearing c, there is secured the beveled gear-wheel E, which meshes with and drives the bevel gear-wheel E', which has integral with it the crank-wheel E², and between the two parts E' and E² the combined crank-wheel and bevel-wheel is journaled in a suitable journal-box provided in the bracket C above its securement to the finger-bar, the beveled gear part E' being in front of the said journal-box and of the finger-bar, and the crank-wheel E² being behind the finger-bar B. The finger-bar B is curved in the arc of a circle, about a center located at the rear of the platform in the vicinity of the rearsill A⁵, some distance grainward from the bend a⁵. As illustrated, (and preferably,) the chord of the arc to which the finger-bar conforms from its intersection with the inside divider to its intersection with the outside divider is substantially at right angles to the direction of advance of the machine.

The fingers b are formed with their edges, respectively, which are on the side farthest away from the middle of the length of finger-bar approximately parallel with the direction of travel, except the middle finger b', which has both edges alike and equally converging toward a line through the point of the finger in the direction of travel. This construction makes only the edges, respectively, of the fingers on the side toward the middle finger b' act as gathering-edges for the grain, the other edges, by reason of extending in the direction of travel, having no tendency to gather the grain laterally. The fingers on the grainward side of the middle finger therefore tend to tip the grain stubbleward as they part it, and those on the stubbleward side of that middle finger tend to tip the grain grainward. This tipping effect being produced before the grain is severed tends to cause it to fall onto the platform with the heads converging, and that is the purpose of this feature of the construction.

F is the sickle. It is curved to conform to the finger-bar B, and is conveniently made of angle-iron bar, with cutters on its horizontal flange. It lies in the angle of the similar but larger and heavier angle-iron which forms the finger-bar.

At a point preferably near the middle of the length of the sickle there is bolted securely to it the radius-arm F', which is flanged or extended into the short cross-arm f¹¹ at the forward end, for the purpose of re-

ceiving the fastening - bolts, and extends thence rearward across the platform from front to rear, and at the rear end is pivoted on the rear sill A⁵ at the center of the arc, to which both the finger-bar and the sickle are conformed. The pivotal connection of the radius-arm F' to the sill A⁵, I make by providing a vertical spindle or pivot f' rigid with the radius-arm F', across the end of it, and providing a bracket F², secured to the sill A⁵, and having suitable step and crown bearings for the ends of such spindle. This bracket F², I make open between the said spindle-bearings, and to the spindle f', between the said bearings, I pivot on a horizontal pivot the radius-lever F³, which extends thence forward, the forward end being lodged in the bearing e², eccentrically located in the crank-wheel E². The spindle f' and the horizontal pivot of the lever F³ form a universal joint for said lever. It should be observed that the axis of the wheels E' E² is radial to the curve of the finger-bar and sickle, and if produced would intersect the axis 25 of the pivotal spindle f'.

Upon the radius-lever F³, a short distance rearward from the crank-wheel E², there is clasped the two-part pitman journal-box E³, and to said journal-box, which has a suitable ear or lug e³ for that purpose, there is connected the pitman or link E⁴, which is connected to the lug f¹⁰ on the radius-arm F'. The points of connection of the link E⁴ to the radius-lever F³ and to the radius-arm F' are preferably equally distant from the pivot-spindle f'. The rotation of the crank-wheel E² causes the radius-lever F³ to describe a cone whose apex is the point of intersection of the horizontal pivot of the said lever with the axis of the spindle f', on which it is pivoted, and at the same time to turn that spindle back and forth on its vertical axis, while the pitman-link E⁴ gives an oscillatory motion to the radius-arm F', which motion it 45 would also receive if sufficiently rigid and rigidly connected to the spindle f' from the axial oscillation of the latter, and by said oscillatory motion of the said radius-arm F' the sickle F is reciprocated back and forth in the arc in which it extends. If it is not convenient to connect the pitman-link E⁴ with the radius-arm F' and the radius-lever F³ at points equally distant from the spindle f', the radius-arm should be pivotally and not 50 rigidly connected to the spindle; but when the pitman-link is connected, as illustrated, at points equally distant from the spindle f' the horizontal movement which would be communicated by the lever F³ through its 55 connection with the spindle to the radius-arm F' is not different from that which would be communicated by the link E⁴ to a greater degree than the necessary play of the joints will accommodate, and the arm F' may therefore be rigid with the spindle, as shown.

The platform under decking G is secured in any convenient manner to the frame-bars

A⁵, A⁶, and A⁷, and to the finger-bar. Preferably cross-bars G' extend from the rear sill to the finger-bar, thereby further stiffening the frame and affording securement for said decking, and the upper decking G³ is supported upon said under decking by blocking or ribs G², located between the concentric feed-bars H. The said upper decking is slotted in arcs of concentric circles about the spindle f', and the feed-bars H are made of metal strips curved to correspond, respectively, to the said curved slots in the deck, and having grain-feeding teeth or fingers projecting through the slots g of the upper decking. If the feed-bars H could be made absolutely rigid and could be rigidly connected to the radius-lever F³, the conical movement of said lever would give to the feed-bars throughout their entire length the movement which is desirable—namely, rising and falling through the slots g and reciprocating in curvilinear paths within said slots—the grainward ends having precisely the same movement as the 90 stubbleward ends, and thus feeding the grain with the same grasp and speed; but it is not possible to make said bars sufficiently rigid, nor to secure them with sufficient rigidity to the lever F³ to prevent the grainward ends of 95 said bars from dropping down and failing to engage the grain, and hence other means have to be resorted to to give both ends substantially the same movement. The means which I adopt for this purpose consist of the 100 radius-lever F⁵, which is connected to the pivoted spindle f' in the same manner as the radius-lever F³. From the spindle f' the lever F⁵ extends to the vicinity of the finger-bar and receives a movement substantially 105 the same as that of the radius-lever F³, such movement being produced by means of the lever F⁶ and the feed-bars themselves co-operating. The lever F⁶ is pivoted upon the frame at f⁶ and passes through the slots f³ 110 and f⁵ in the levers F³ and F⁵, respectively, to make sliding pivotal connection with said levers, the distances from f³ to f⁶ and f⁵, respectively, being proportional to the distances from f³ to f⁶ and f', respectively. The feed-bars are loosely connected to the radius-levers F³ and F⁵, and kept from moving longitudinally with respect thereto by suitable stop-pins or collars h. The lever F⁵ will receive the same vertical movement as the lever 120 F³ by means of the lever F⁶, and will receive the same horizontal movement as the lever F³ by means of the feed-bars H, and these two movements being simultaneously communicated give to said lever F⁵ the resultant rotary movement, substantially the same as that of the lever F³. Thus the two ends of the feed-bars H, receiving substantially the same movement, take the same movement throughout their entire lengths. Since the 125 lever F⁶ is designed to communicate to the lever F⁵ only the vertical movement of the lever F³, its sliding pivotal connections to both levers F³ and F⁵ are by longitudinal slots

f^3 and f^5 , as described, and by means of those slots the levers F^3 and F^5 play to the extent of their horizontal movements on the lever F^6 . To keep the lever F^6 in the proper vertical plane, a guide F^{60} may be provided at any convenient point on the platform-decking. The holes f^3 and f^5 are elongated, making them slots, as described, to allow for the circumferential movement of the levers F^3 and F^5 .

I have described the connections of the feed-bars H to the levers F^3 and F^5 as loose merely because rigidity at those connections is not essential; but, in fact, no movement will occur at those points, and the levers F^3 and F^5 may be rigidly connected together and provided with a common pivotal connection to the spindle f' without in any respect altering the movement of the feed-bars.

A preferred modification consists in making the lever F^6 without any pivotal action upon the levers F^3 and F^5 , and connecting these rigidly-joined levers by a single horizontal pivot to the pivot f' , and providing a sliding pivotal connection for the lever F^6 on the frame. This construction, which is shown in Fig. 2, makes all the parts $F^3 F^5 F^6$ and the feed-bars H move as one rigid structure, and they are therefore shown as rigidly united. In this construction the parts F^3 , F^5 , and F^6 may be considered as constituting a frame for the support and actuation of the feed-bars H .

In defining the relations between the distances from slot f^5 to spindle f' and pivot f^6 , and from slot f^3 to spindle f' and pivot f^6 , the mean position of the levers F^3 and F^5 on the lever F^6 and of said lever F^6 in the slots are the positions to be considered; and in the structure shown in Fig. 2 the slot in which the lever or lever-arm F^6 gets its sliding pivotal action should be located in the horizontal plane of the pivot of bars $F^3 F^5$ to the spindle f' and in a horizontal line through said pivot parallel to the chords of the arcs of movement of the feed-bars H .

It will be obvious that any number of lever-arms rigid with the rigid structure composed of bars $F^3 F^5 F^6$ and the feed-bars H might be extended through sliding pivotal bearings in line with that of the lever F^6 , and that such additional arms so connected would not alter the movement of this structure. One such additional arm F^7 is shown in dotted lines in Fig. 2. Inspection of this structure will make it evident that the action may be considered as that of a plane rocking over a horizontal line parallel with the chords of the arcs of movement of the feed-bars, and at the same time oscillating in the direction of its own extent about a point in said horizontal line, such point being the center of said arcs; and considering the form shown in Fig. 1 it will be evident that the bars F^3 and F^5 and the feed-bars H move as a unitary structure, and that the movement of such structure as caused by the wheel E^2 and controlled by the lever

F^6 is also correctly described as last above stated, and this may therefore be considered the most generic conception of the movement. The parts F^3 , F^5 , and F^6 in both the forms described are bars having the function of connecting the feed-bars and forming a supporting-frame for the same; but parts F^5 and F^6 cease to be distinctly levers when they are made rigid with part F^3 , as in the structure shown in Fig. 2, wherein they become in effect arms of part F^3 , which in that structure, as well as in the other form illustrated, operate as a lever.

It will be obvious that only so much of the wheel E^2 as would make up a crank-arm reaching to the bearing e^2 is essential to the movement produced, and in referring to this wheel in my claims I design to include only so much of it.

The operation of this mechanism is, first, as described, by reason of the form of the fingers, to cause the grain to fall upon the platform with the heads converging toward the pivot f' . Since the stroke or movement of the feed-bars H is greater in proportion to their distances forward of that pivot, their action upon the grain wheels the grain about that pivot and accumulates it at the stubble side of the platform in a position oblique to the line of travel of the machine, and this is accomplished without employing any special devices for turning the grain in addition to the platform-conveying mechanism above described.

In view of the operation of this mechanism it is thought important that the grain should, if possible, be caused to fall upon the platform with the heads converging, as described, and in addition to making the fingers b of the form described, whereby they tend to lean the grain before it is severed, I construct the reel so that it will tend to produce a like result by making its bats R in curved form, substantially conforming to the curvature of the bar and sickle. The bats thus formed are secured to the reel-arms R' in such relation thereto as respects the direction of their curve that each bat will be approximately parallel to the sickle at the position which the bat occupies when the grain engaged by it is being severed. Obviously, this position will vary somewhat as the reel is adjusted to the different conditions and heights of the grain; but the variation is not sufficient to prevent the attainment, substantially, of the result sought.

I have in the drawings made no illustration of any mode of adjusting the reel, since that does not pertain to my present invention, and the construction of the reel and its driving mechanism, which I have shown, except as respects the curved bats described, is merely conventional, and I design such curved bats to be applied to any form of reel driven by any desired mechanism. In the drawings I have simply shown the reel-shaft R^2 journaled in standards R^3 and R^4 , secured to the

forward frame-bar A², said reel-shaft having at its end the sprocket-wheel r², which is driven by a chain R⁵, which receives its motion from the sprocket-wheel r⁵ on the drive-wheel axle.

When concentrically-operating conveying devices are combined with a straight sickle and located behind it, difficulty is experienced because the grain cut at the grain end of the sickle and falling prostrate behind it if swept in the curved path of the devices has its butts carried forward of the line of the cut at the middle part, and provision must be made for moving the grain endwise to prevent this difficulty. By curving the sickle in conformity to the curved path of the conveying mechanism this difficulty is avoided, and by employing such concentrically-operating conveying devices immediately behind the sickle I am able to utilize the entire width of both the platform and whatever parts may necessarily intervene between it and the drive-wheel for turning the grain to the desired position and binding it. The bar A¹⁰ is made of round iron pipe, and parallel to it at a little distance stubbleward is secured a similar tubular bar A¹¹. Both of these bars are secured at their rear ends to the bar A⁹ and extend a considerable distance forward of the bar A⁴, to which they are also secured. Their direction is substantially parallel to the oblique line at which the feed-bars H deliver the grain—that is, parallel to a radius through the pivot f' and the stubbleward end of the forward bar H at its most stubbleward position. Upon these two bars A¹⁰ and A¹¹ the binder-frame is supported and adapted to slide. Said binder-frame is of the usual form, having two parallel horizontal arms L' and L² connected by the standard L. From the standard L there are extended at the forward end the bracket-like arms L²⁰ and L²¹, and from the lower arm L², at the rear end, the arms L²² and L²³, which afford the bearings of said frame on the bars A¹⁰ and A¹¹. From the forward lower corner of the binder-frame there is also extended the arm or bracket L²⁴, which affords a bearing l²⁴ for the forward end of the shaft M. Said shaft M has another bearing near its rear end, which it obtains in the bracket L²⁵. This shaft M is the shaft of the beveled gear-wheel D⁶. It is square between its bearings in brackets L²¹ and L²⁵ and slides through the hub of the wheel D⁶, which has a corresponding square opening. At the rear end of the shaft M is secured the packer-crank M', and at the forward end is secured the sprocket-wheel M², which, by means of the chain m², communicates power to the wheel M³, journaled on the binder-frame, and being the main binder-driving wheel, from whose shaft power is communicated to the remainder of the binder mechanism, all of which is of familiar character and not illustrated in detail and need not be herein described.

Upon the sill A' there is secured a bracket

N, at the upper end of which there is formed the notched segment N'. In this bracket N there is journaled the vertical rock-shaft n, 70 which has at the upper end the lever-arm N², which extends stubbleward in convenient reach of the driver from the seat, and at the lower end the lever-arm N³, which extends grainward and is connected by the link N⁴ to 75 the binder-frame, to which said link is pivoted at n⁴. The locking-dog n², operated in familiar manner, as illustrated, is connected to the arm N², and engages the segment N'. By means of said rock-shaft and its lever-arms 80 the binder may be moved back and forward, sliding on the bars A¹⁰ and A¹¹, and by means of the dog n² and segment N' may be locked at any position desired.

By extending those of the feed-bars H, 85 which are rearward from the vertical plane of the needle stubbleward nearly to the vertical plane of the needle rock-shaft I make them serve as packers, dispensing with a separate packer behind the needle. 90

Upon the oblique portion of the sill A⁵, which extends, as already stated, from the vertical plane of the drive-wheel axle obliquely grainward and rearward, and which, as illustrated, lies at an angle of about forty-five degrees to the axle, I mount in suitable brackets a⁵⁰ and a⁵¹, one at each end, the rock-shaft P. This rock-shaft I provide with crank-arms P', of which the forward one is the longest and the rear the shortest and the intermediate ones of intermediate lengths. To the ends of these crank-arms are pivoted arms P², which are slightly bent near their pivots p², so that their direction is somewhat more nearly rearward than the vertical planes 105 of the cranks P'. These arms P² toward their rear ends are bent so that they terminate almost directly rearward, as illustrated. The cranks P' normally extend almost horizontally toward the binder and conveyer 110 platform, and the arms or bars P², extending from their pivotal connections p², lie on top of the shaft P, so that said arms P² also normally extend almost in a horizontal direction. At the stubbleward and forward ends of the 115 shaft P it is provided with a lever-arm P³, by means of which the shaft P may be rocked in its bearings; and the bracket a⁵¹ has formed upon it the notch a⁵². A suitable locking-dog p³, operated in the customary manner, is 120 provided to engage said notch.

Around the shaft P, between the foremost crank-arm P' and the bracket a⁵¹, is coiled the spring P⁴, one end of which is secured to said bracket and the other to said crank, the 125 spring being coiled in such direction as to tend to rock the shaft to carry the arms P' over toward the binder. This structure, comprising the shaft P, crank-arms P', and arms P², constitutes a sheaf-carrier, onto whose arms 130 P² the bundles are discharged from the binder. When any desired number of sheaves are accumulated on said arms, the driver will release the locking-dog p³ from the notch a⁵²,

and the weight of the bundles overcoming the tension of the spring P^4 will cause the carrier-arms P^2 to descend and allow the bundles to slide off to the ground. As soon as 5 the bundles are discharged the spring P^4 , reacting and being sufficiently strong for that purpose, will rock the shaft P , throw the crank-arms P' back to their horizontal position, and lift the carrier-arms P^2 , also, to their 10 original position, ready to receive a new load. In the dumping movement of the carrier-arms they slide and rock over the shaft P until their rear ends touch the ground, and then are lifted at their opposite ends, where 15 they are pivoted to the cranks P' until said ends stand vertically above the shaft P distances equal to the lengths, respectively, of said cranks. They therefore are caused to stand at a steeper inclination than if they were 20 merely pivoted over the shaft P , or were rigid with it and tipped by it, the length of said cranks being added to the height of the shaft P from the ground in giving them their inclination. It will be seen that this structure 25 permits the bundles to be discharged with their butts in the rear of the drive-wheel, and by reason of the curvature of the ends of the carrier-arms P^2 and the greater lengths of the forward cranks P' the butts of the 30 sheaves are caused in the process of dumping to be turned round, so that they will lie upon the ground almost at right angles to the direction of travel, as if discharged directly rearward. It will be noticed, also, that no action 35 of the driver is necessary either to dump or restore the carrier except the releasing of the locking-dog p^3 , the dumping being then effected by the weight of the bundles, and the restoration being effected by the reaction of the spring P^4 after the bundles are discharged.

I claim—

1. In combination, substantially as set forth, the curved finger-bar and the fingers thereof, those fingers which stand grainward from 45 a selected fore-and-aft vertical plane having their foremost points, respectively, as far grainward as any point on their grainward edge, and those fingers which stand stubbleward from such selected plane having their foremost points, respectively, as far stubbleward as any point on their stubble- 50 ward side, the edges toward the selected plane slanting from the point back toward such plane, whereby the fingers tend to lean the 55 grain toward such selected plane.

2. In combination with the curved finger-bar, the sickle having the same curvature and resting upon the bar and having a radius-arm pivoted at the center of curvature, 60 a wheel having its axis in a radius of the same curve, and a radius-lever F^3 , pivoted at the center of curvature, having an eccentrically-located bearing in the wheel E^2 , whereby it describes the surface of a cone as 65 the wheel E^2 revolves, and a link E^4 , pivoted to said radius-lever F^3 and to the radius-arm of the sickle, whereby the sickle is recipro-

cated in the arc of its curvature, substantially as set forth.

3. In combination with the platform slotted 70 in concentric curves, the wheel E^2 , having its axis in a radius of such curves, the radius-lever F^3 , eccentrically pivoted to such wheel and pivoted to the frame at the center of curvature, and the toothed feed-bars H , secured to the lever F^3 , whereby they are reciprocated in the arcs of their curvature, substantially as set forth.

4. In combination with the curved finger-bar and the sickle having the same curvature 80 and reciprocated in the arc of its curvature, the feed-bars H , curved concentrically with the finger-bar and the sickle, and the means, substantially as described, whereby they are reciprocated in the arcs of curvature, respect- 85 ively, substantially as set forth.

5. In combination with the curved finger-bar, the sickle having the same curvature and having the radius-arm pivoted at the center of curvature, the wheel E^2 , whose axis 90 is in a radius of the same curve, the radius-lever F^3 , pivoted at one end at the center of curvature and at the other pivoted eccentrically to said wheel, the link E^4 , pivoted to said radius-lever and radius-arm, the concentric 95 feed-bars H , secured on said lever F^3 , whereby the wheel E^2 reciprocates both the sickle and the feed-bars in the arcs of their curvature, respectively, substantially as set forth.

6. In combination with the platform-frame 100 and the wheel E^2 , journaled thereon, the bar F^6 , concentric feed-bars H , and the lever F^3 , said lever F^3 being connected at one end to the frame by a universal joint located substantially at the center of curvature of the 105 feed-bars, and having the other end connected to and rotated by the wheel E^2 , said feed-bars being each at one point supported by and partaking of the motion of the lever F^3 , and being each controlled, also, in respect to said motion by the bar F^6 , said bar being supported by and partaking of the vertical motion of the lever F^3 , and being supported, also, by the harvester-frame at one point and rocking freely over its said frame-support, the connection of said lever to one of its said supports being a sliding connection, substantially 110 as set forth.

7. In combination with the platform-frame, the wheel E^2 , journaled thereon, the concentrically-curved feed-bars, and their supporting and actuating frame, said frame being connected at one point to the wheel E^2 eccentrically with respect to said wheel, and being at another point connected to the platform-frame by a universal joint located substantially at the center of curvature of the feed-bars, and at a third point having a sliding pivotal connection with the platform, such sliding connection being substantially in a 115 horizontal line through the universal joint parallel with the chords of the arcs of movement of the feed-bars, substantially as set forth.

8. In combination with the platform slotted in the arcs of concentric circles about a center at the rear of such arcs, feed-bars curved to correspond to said slots, and bars which connect them, the entire structure composed of said feed-bars, and their connecting parts being connected to the frame by a universal joint composed of a horizontal and a vertical pivot located at the center of curvature of the feed-bars, substantially as set forth.

9. In combination with the platform-frame and the wheel E², journaled thereon, concentrically-curved feed-bars II, and a feed-bar-supporting frame comprising the lever F³ and bar F⁵, both connected at the rear end by a universal joint to the platform-frame, said joint being located substantially at the center of curvature of the feed-bars, the lever F³ being at its forward end connected to and rotated by the wheel E², and the bar F⁶ connected to the feed-bar-supporting frame and to the platform-frame, one of said connections being a sliding pivotal connection, said bar rocking freely over its platform-frame connection, its connection with the feed-bar-supporting frame being made both at the lever F³ and the bar F⁵, the distances from the point of connection of F⁶ and F³ to the universal joint and to the platform-frame connection of F⁶, respectively, being proportional to the distances from the point of connection of F⁵ and F³ to the same two points, respectively, substantially as and for the purpose set forth.

10. In combination with the feed-bars II, curved concentrically with the finger-bar and sickle, and the means, substantially as described, whereby said bars are reciprocated in the arcs of their curvature, respectively, the binder located at the delivery end of the feed-bars and between the same and the vertical plane of the drive-wheel, and having its operating-shafts oblique to the direction of travel of the machine, substantially as and for the purpose set forth.

11. In combination with the feed-bars II, curved concentrically with the finger-bar and sickle, and the means, substantially as described, whereby said feed-bars are reciprocated in the arcs of their curvature, respectively, a portion of said feed-bars terminating in a line substantially radial to the arcs of curvature of the feed-bars and oblique to the direction of travel, and the binder located at the delivery end of such obliquely-terminating bars, having its operating-shafts parallel to such oblique line, substantially as and for the purpose set forth.

12. In combination, in a platform-conveyer,

feed-bars operating in vertical planes to feed the grain toward the binder, the binder having the packer operating in a vertical plane substantially parallel to the vertical planes of movement of the feed-bars, those feed-bars which are forward of the vertical plane of the packer terminating grainward from the vertical plane of the packer-shaft, and those which are rearward of the vertical plane of the needle terminating stubbleward from the vertical plane of the packer-shaft, substantially as set forth.

13. In combination with the platform-frame having the sill A⁵ extending obliquely from the vicinity of the drive-wheel axle grainward and rearward, the binder located forward and grainward of said sill, and the rock-shaft P, journaled on said sill, having crank-arms P', which extend normally toward the vertical planes of the binder-shafts, and the carrier-arms P², pivoted to said crank-arms, extending from said pivotal connection back, and further supported by the shaft P, substantially as set forth.

14. In combination with the harvester-frame, the horizontal rock-shaft P, journaled thereto, having crank-arms P', carrier-arms P², pivotally connected to the crank-arms, extending from said pivotal connection back across and further supported by resting on the shaft P, and the spring P⁴, secured at one end to the shaft and at the other end to the shaft-bearing and tending to rock the shaft to throw its crank-arms toward the binder, substantially as set forth.

15. In combination, substantially as set forth, the wheel-frame comprising the sills A and A', A², and A³, secured together at their four intersections, the sill A³ being bent forward and grainward from its intersection with sill A', and the sill A⁵ secured to the sill A' and extending across and secured to the oblique portion of the sill A³.

16. In combination with the inner sill A', the rear sill A³, secured thereto and extending obliquely forward and grainward from said connection, the sill A⁵, also secured to the sill A' at a point forward of the connection of the sill A³, and extending obliquely rearward and grainward, said sills A³ and A⁵ being secured together at their intersection, the bar A⁴, secured to the sill A' and to the oblique portion of the sill A³, and the bar A⁷, secured to the sill A⁵ and to the bar A⁴, substantially as and for the purpose set forth.

WILLIAM F. OLIN.
